UNITED STATES PATENT OFFICE.

GEORGE F. RICKER, OF CAMBRIDGEPORT, MASSACHUSETTS.

CARPET-BEATING MACHINE.

SPECIFICATION forming part of Letters Patent No. 274,224, dated March 20, 1883.

Application filed November 22, 1882. (No model.)

To all whom it may concern:

Be it known that I, GEO. F. RICKER, of Cambridgeport, in the county of Middlesex and State of Massachusetts, have invented certain new and useful Improvements in Carpet-Beating Machines, of which the following, taken in connection with the accompanying drawings, is a specification.

My invention relates to a machine for beating carpets to remove dust and dirt therefrom, and especially to the construction of the carpet-supporting bed and the dust-receptacle beneath the same, and the manner of applying the beaters to the beater-cylinder; and it consists in a novel construction of the carpet-supporting bed or rack and the dust-receptacle beneath said bed, and a novel mode of applying the beaters to the operating-cylinder, all of which will be readily understood by reference to the description of the drawings and to the claims to be hereinafter given.

Figure 1 of the drawings is a vertical transverse section of my improved carpet-beating machine. Fig. 2 is a horizontal section of the same on line $\alpha\alpha$ on Fig. 1. Fig. 3 is a partial vertical longitudinal section on line yy on Figs. 1 and 2; and Figs. 4 and 5 are partial vertical sections, illustrating the construction of the carpet-supporting bed or rack drawn to an enlarged scale.

A is the beating-chamber, provided with the door B, hinged at its upper edge, and adapted to be turned upward for the purpose of introducing the carpet C into the chamber A.

D is the dust receptacle, having its two longest sides, $a a'$, inclined, as shown, and supporting at its top the carpet-supporting grating E, composed of a series of metal rods, $b b$, supported in slotted metal plates c and c' , secured to opposite sides of said receptacle and extending longitudinally thereof, as shown in Figs. 3, 4, and 5. The rods $b b$ extend through the plates c and c' , and rest upon the sheets of rubber, leather, or other soft non-resonant material, d and d' , secured to the fixed portions of the sides $a a'$ of the dust-receptacle. To keep the rods $b b$ in position, endwise strips e and e' , of wood, are secured to the upper edges of the walls a and a' , respectively, to the upper sides of which are respectively secured by the guard-strips f and f' the strips of rubber, leather, or other non-resonant material, g and g' ,

which project over the ends of the rods $b b$, and against which said rods strike as they bound upward after being struck by the beaters, the holes in the plates c and c' being slotted vertically to permit such upward movement of the rods for the purpose of more effectually removing the dust and discharging it into the receptacle D. The object of the non-resonant strips d , d' , g , and g' is to reduce or deaden the noise that would otherwise be made by the rods $b b$ while being whipped by the beaters. The strips e and e' are permanently secured to the wall a' by screws or nails, as shown in Fig. 5. To facilitate the insertion and removal of the rods $b b$, the strips e and e' are secured together, clamping the rubber or leather strip g between them, and the strip e is hinged at h to the wall a , so that it may be turned down into the position indicated in dotted lines in Fig. 4, when the rods $b b$ may be readily drawn out through the holes in the plate c ; or a new rod may be inserted, and the strips e and e' are turned up again into the position shown in full lines in said Fig. 4, in which position it may be secured by any suitable fastenings—such, for instance, as one or more buttons, locks, or catches. (Not shown in the drawings.)

F is the beater-cylinder, extending lengthwise of the chamber A and mounted in suitable bearings in the end walls of said chamber, and having mounted upon its shaft the driving-pulley G, as shown in Fig. 2. The cylinder F may be made solid, as shown; or it may be made hollow, if desired, and has set in its periphery two or more longitudinal rows of metal pins, i , provided with heads, as shown in Figs. 1 and 2, said pins being so set in the cylinder that the pins in one row shall revolve about the axis of the cylinder F in planes between the planes of revolution of the pins in the other row.

H H are the beater-straps, made of leather, rubber, or other tough flexible material, and each connected at one end to one of the pins i , as shown.

I I are guard-strips, made concavo-convex in cross-section, and having transverse grooves $j j$ cut across their inner or concave sides, corresponding in number and location to the number and location of the pins i in the row of pins to which each strip is to be applied, said grooves being of sufficient width and depth to receive

the beater-straps H, as shown. In the bottom of each of the transverse grooves, j, is formed a circular recess to receive the head of the pin i, and the corners of the strips I I at one side of each of the grooves jj is rounded upward to prevent the sharp corner from cutting the beater-strap, all as shown in Fig. 1. The arrangement of the beater-straps in the different rows is such that the straps in one row will strike upon the carpet between the points where the straps in the preceding row struck, and the guard-strips I I are firmly secured to the cylinder F by screws kk, as shown in Fig. 2.

Suitable draft-pipes (not shown in the drawings) are to be connected with the outlets of the dust chamber or hopper D and to an exhaust-blower, (also not shown,) as a means of removing the dust and dirt as it is beat from the carpet, and also helping to remove the dirt from the carpet, and acting as a disinfectant by thoroughly airing the carpet while it is being beaten.

J J are two pipes communicating with the interior of the chamber A and leading to the blower or connecting to the other pipes leading thereto, for the purpose of removing the dust from above the carpet.

K is a door opening into the dust-receptacle D, and L is a slatted rack to receive the carpet as it is delivered from the bed.

I am aware of the state of the art as embodied in Letters Patent of the United States No. 180,075, July 18, 1876; No. 195,357, September 18, 1877, and No. 164,274, June 8, 1875, and I do not claim anything therein contained; but

What I claim as new, and desire to secure by Letters Patent of the United States, is—

1. In a carpet-beating machine, a carpet-supporting bed or rack composed of a series of rods mounted in vertically-slotted bearings, substantially as and for the purposes described.

2. In combination with the beater-cylinder of a carpet-beating machine, the series of rods b b, mounted in vertically-slotted bearings in the plates c and c', and the non-resonant strips d, d', g, and g', all arranged and adapted to operate substantially as and for the purposes described. 45

3. The beater-cylinder F, in combination with two or more longitudinal rows of pins, i i, set therein, two or more series of flexible beaters, H H, each attached by one end to one of said pins, and two or more concavo-convex guard-strips, I I, all arranged and adapted to operate 55 substantially as described.

4. In combination with the beater-cylinder and carpet-supporting bed or rack, the dust-receptacle D, having its two side walls inclined and its two end walls vertical, and provided with two or more discharge-openings in its bottom, arranged to discharge the dust from the middle or ends of said hopper equally, substantially as and for the purposes described. 60

5. In combination with a beater-cylinder, a carpet-supporting bed or rack, and a dust-receptacle beneath said bed, provided with discharge-openings, the pipes J J, communicating with the interior of the chamber A and adapted to convey the dust therefrom, substantially as described. 70

6. In a carpet-beating machine, the combination of the series of rods b b, the slotted plates c and c', and the strips e and f, secured together and hinged, substantially as and for 75 the purposes described.

In testimony whereof I have signed my name to this specification, in the presence of two subscribing witnesses, on this 20th day of November, A. D. 1882.

GEORGE F. RICKER.
